ATTORNEY,

UNITED STATES PATENT OFFICE.

JOHN J. COMER, OF CHICAGO, ILLINOIS, ASSIGNOR TO AUTOMATIC ENUNCIATOR COMPANY, OF CHICAGO, ILLINOIS, A CORPORATION OF ILLINOIS.

TELEPHONE SYSTEM.

1,185,879.

Specification of Letters Patent.

Patented June 6, 1916.

Application filed December 19, 1912. Serial No. 737,658.

To all whom it may concern:

Be it known that I, JOHN J. COMER, a citizen of the United States of America, and resident of Chicago, Cook county, Illinois, have invented a certain new and useful Improvement in Telephone Systems, of which the following is a specification.

My invention relates to improvements in telephone systems, but more particularly to those systems which are employed for transmitting vocal or instrumental music. In this connection it is found that it is advantageous to employ what is known as a differential transmitter—that is, a transmitter which consists of a pair of relatively stationary electrodes between which is located a relatively movable electrode. In using this type of transmitter, it has heretofore been difficult to provide a circuit arrangement which would transmit over the line the total combined effect of the two parts of this differential transmitter, as the variations of current produced by one half of the transmitter would have a tendency to counteract or buck the variations produced by the other half, unless special provisions were taken to prevent such operations.

The object of my invention is to provide an improved circuit arrangement whereby such a transmitter can be employed and in which the total accumulative effect is obtained, there being no tendency of one part of the transmitter to buck or oppose the other part. By multiplying together a plurality of these transmitters, and then connecting them to a plurality of line circuits in which are located suitable amplifiers, I am able to employ as many as ten receivers on each line circuit, and where ten of such line circuits are taken from the bus bar it will be seen that I am able to furnish operating current to one hundred receivers from a single set of transmitters.

My invention will be more readily understood by reference to the accompanying drawings, in which—

Figure 1 shows, diagrammatically, a circuit arrangement as applied to a single line circuit. Fig. 2 shows a similar arrangement, showing in addition the manner in which a plurality of these circuits are combined together. Fig. 3 is a diagrammatic view showing more clearly the manner in

which the circuit arrangement is in the form of a Wheatstone bridge.

I have shown, diagrammatically, a microphone transmitter consisting of the stationary electrodes 3 and 4 and a movable electrode 5. This transmitter is bridged across the line conductors 6 and 7, one of these conductors being connected to each of the stationary electrodes respectively of the transmitter. The movable electrode 5 is connected to the grounded pole of the battery B, while the opposite pole of the battery is connected to the two line conductors through the resistance coils 8 and 9. A series of receivers 10 are bridged across the line circuit, which receivers are conductively separated from the transmitter by means of the condensers 11 and 12.

In Fig. 2, I have shown the manner in which a series of these transmitters are combined. It is merely necessary to connect the various pairs of line conductors in multiple to the same pole of the battery, and likewise the movable electrode of the various transmitters in multiple connection to the opposite pole of the battery. The line conductors are then connected to the bus bars 13 and 14, to which bus bars the amplifiers 15 are connected. The condensers 11 and 12 are inserted in the conductors 6 and 7, between the bus bars 13 and 14 and the point where the transmitters are connected to the conductors. The location of these condensers is quite important, as I find that much more efficient results are obtained by placing these condensers in the conductors 6 and 7 before they are connected to the bus bars, than by placing these condensers between the bus bars and the amplifiers. These amplifiers can be of any desired construction, and they form no part of my invention, and I merely illustrate the same diagrammatically, as the construction and operation of these amplifiers are well understood in the art. These amplifiers then receive the current from the bus bars and repeat the same over the line conductors, across which are bridged the receivers 10. This circuit arrangement and the operation of the same can be more clearly understood by having reference to Fig. 3. It will be seen that the fixed resistances 8 and 9 form two sides of a Wheatstone bridge,

while the variable resistances for the other

two sides of the bridge consist of the two parts of the transmitter, the battery being connected at a point between the two parts of the transmitter.

- 5 It is thought that the operation of the system will be clearly understood. The granular material of the transmitter while at rest furnishes a comparatively low resistance, but the resistance coils 8 and 9 are 10 of sufficiently high resistance to prevent the battery from becoming short circuited at this time. As soon as the transmitter is set in vibration, however, the resistance of the granular material rises very rapidly, and 15 the resistance of the granular material then forms a large percentage of the total resistance. Accordingly, the variations in this resistance due to the operation of the transmitter cause a greater variation of potential at the points of the bridge to which the 20 receivers are connected and, therefore, produce an amplified effect on those receivers. When a plurality of these circuits are combined, as in Fig. 2, the fluctuations of current in the line conductors, due to the variation in resistance of the granular material, are transmitted over these conductors through the condensers 11 and 12 to the bus bars 13 and 14, from which this current is 25 taken off and passes through the amplifiers 30 and 15. The presence of the condensers 11 and 12 prevents any local circuits being set up through these bus bars to the other transmitters connected in multiple, and I find 35 that by this circuit arrangement that the effects of the various transmissions are combined together in a very efficient manner, and there appears to be little or no tendency for variations set up by one transmitter to 40 counteract or buck the variations set up by another transmitter. I find that this system is particularly useful in the transmission of music where each one of the series of transmitters will receive the vibrations from 45 a particular instrument and then the combined effect is transmitted to the bus bars, to which I connect a number of amplifiers, and each one of the amplifiers then supplies ten or more receivers.
- 50 While I have shown one particular embodiment of my invention, it will be understood that I do not wish to be limited to the exact construction shown and described.
- What I claim as my invention is:
- 55 1. In a telephone system, a plurality of pairs of line conductors, the conductors of each pair being connected together at one end, and connected in multiple to one pole of the battery, a transmitter bridged across 60 each pair of said line conductors, each of said transmitters including three electrodes, the central electrodes of which are connected in multiple to the opposite pole of the battery, and multiple connections between corresponding line conductors of each of said 65

pairs at a point beyond the connection of said transmitters to said line conductors.

2. In a telephone system, a plurality of pairs of line conductors, the conductors of each pair being connected together at one end and connected in multiple to one pole of the battery, a transmitter bridged across each pair of said line conductors, each of said transmitters including three electrodes, the central electrodes of which are connected in multiple to the opposite pole of the battery, multiple connections between corresponding line conductors of each of said pairs at a point beyond the connection of said transmitters to said line conductors, and condensers inserted in said line conductors between said transmitter and said last-mentioned multiple connection.

3. In a telephone system, a plurality of pairs of line conductors, the conductors of each of said pairs being connected together at one end and multiplied to one pole of a battery, a transmitter bridged across each of said pairs of line conductors, said transmitters comprising a pair of outer electrodes and a central electrode, one of said outer electrodes being connected to one of said line conductors, and the other outer electrode connected to the other line conductor, and said central electrode being connected to the opposite pole of the battery, and a pair of bus bars connected in multiple to the corresponding line conductors.

4. In a telephone system, a plurality of pairs of line conductors, the conductors of each of said pairs being connected together at one end and multiplied to one pole of a battery, a transmitter bridged across each of said pairs of line conductors, said transmitters comprising a pair of outer electrodes and a central electrode, one of said outer electrodes being connected to one of said line conductors, and the other outer electrode connected to the other line conductor, said central electrode being connected to the opposite pole of the battery, a pair of bus bars connected in multiple to the corresponding line conductors, and condensers inserted in said line conductors at a point between said bus bars and said transmitters.

5. In a telephone system, a plurality of pairs of line conductors, the conductors of each of said pairs being connected together at one end and multiplied to one pole of a battery, a transmitter bridged across each of said pairs of line conductors, said transmitters comprising a pair of outer electrodes and a central electrode, one of said outer electrodes being connected to one of said line conductors, and the other outer electrode connected to the other line conductor, and said central electrode being connected to the opposite pole of the battery, a pair of bus bars connected in multiple to the corresponding line conductors, a plurality of

amplifiers connected in multiple to said bus bars, and a plurality of receivers operatively connected with each of said amplifiers.

6. In a telephone system, a plurality of pairs of line conductors, the conductors of each of said pairs being connected together at one end and multiplied to one pole of a battery, a transmitter bridged across each of said pairs of line conductors, said transmitters comprising a pair of outer electrodes and a central electrode, one of said outer electrodes being connected to one of said line conductors, and the other outer electrode connected to the other line conductor, and 15 said central electrode being connected to the opposite pole of the battery, a pair of bus bars connected in multiple to the corresponding line conductors, condensers inserted in said line conductors at a point 20 between said bus bars and said transmitters, a plurality of amplifiers connected in multiple to said bus bars, and a plurality of receivers operatively connected with each of said amplifiers.
- 25 7. In a telephone system, a plurality of circuits each comprising a pair of fixed resistances forming two legs of a Wheatstone bridge, and a microphone transmitter having a pair of variable resistances, one in

each of the other legs of said bridge, a battery having one pole connected in multiple between the pairs of fixed resistances, and the other pole connected in multiple to a point between said variable resistances and a plurality of receiving instruments connected in multiple to points between said fixed and variable resistances.

8. In a telephone system, a plurality of circuits each comprising a pair of fixed resistances forming two legs of a Wheat- 40 stone bridge, and a microphone transmitter having a pair of variable resistances one in each of the other legs of said bridge, a battery having one pole connected in multiple between the pairs of fixed resistances and 45 the other pole connected in multiple to a point between said variable resistances and a plurality of receiving instruments connected in multiple to points between said fixed and variable resistances and in series 50 with condensers.

Signed by me at Chicago, Illinois, this 16th day of December, 1912.

JOHN J. COMER.
